US00D862544S

(12) **United States Design Patent** (10) **Patent No.:** **US D862,544 S**
Lin (45) **Date of Patent:** **** Oct. 8, 2019**

(54) **WELDING MACHINE CASE**

(71) Applicant: **ZHEJIANG LIN LONG WELDING EQUIPMENT CO., LTD.**, Wenlin, Zhejiang (CN)

(72) Inventor: **Yang Lin**, Zhejiang (CN)

(73) Assignee: **ZHEJIANG LIN LONG WELDING EQUIPMENT CO., LTD.**, Shanglin Village, Chengxi Sub-District, Wenlin, Zhejiang (CN)

(**) Term: **15 Years**

(21) Appl. No.: **29/562,204**

(22) Filed: **Apr. 22, 2016**

(51) LOC (12) Cl. **15-09**

(52) U.S. Cl.

USPC **D15/144**

(58) **Field of Classification Search**

USPC D15/144, 144.1, 144.2; D13/110; D14/349

CPC . B23K 9/10; B23K 9/32; B23K 9/133; B23K 9/327; B23K 10/00

See application file for complete search history.

(57)

CLAIM

The ornamental design for a welding machine case, as shown and described.

DESCRIPTION

FIG. 1 is a front elevation view of a welding machine case showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a right perspective view thereof.

The portions of the article shown in broken lines form no part of the claimed design.

1 Claim, 5 Drawing Sheets
